No. 890,155.

PATENTED JUNE 9, 1908.

J. G. MASTIN.
FIRE EXTINGUISHER.
APPLICATION FILED FEB. 5, 1908.

UNITED STATES PATENT OFFICE.

JAMES G. MASTIN, OF CHICAGO, ILLINOIS.

FIRE-EXTINGUISHER.

No. 890,155.

Specification of Letters Patent.

Patented June 9, 1908.

Application filed February 5, 1908. Serial No. 414,386.

To all whom it may concern:

Be it known that I, JAMES G. MASTIN, citizen of the United States, residing at Chicago, in the county of Cook and State of Illinois, have invented certain new and useful Improvements in Fire-Extinguishers, of which the following is a specification.

My invention relates to certain new and useful improvements in fire extinguishers, and comprises certain constructions and combinations whereby the device is rendered highly efficient and effective for the purpose for which it is designed.

The structure shown and described in this application is a modification of that shown and described in my application filed December 23rd, 1907, Serial No. 407,725.

In the accompanying drawings wherein I show the preferred form of my invention the same part is designated by the same reference numeral wherever it occurs.

Figure 1 is a perspective view of a fire extinguisher embodying my invention; Fig. 2 is a central longitudinal section; Fig. 3 is a section taken on line 3, 3 of Fig. 2; Fig. 4 is a sectional view showing a modified form of outlet valve, and Fig. 5 is a detail view partly in section showing the manner of securing the cam levers in their bearings.

1 designates the container or casing in the upper end of which is secured the ring 2, the ring being secured to the upper edge of the container in any desired manner. The ring 2 is provided with the outwardly projecting circumferential shoulder 3 formed with a cam surface 4 on its lower side and on its upper side at its inner edge with a bead 5.

6 designates the closure cap which is adapted to carry and support all the operating parts of the device and to close the opening in the ring 2, so that when the cap is removed to fill the extinguisher all the operating parts of the device are lifted out of the casing or container, so that they are readily accessible for cleaning, inspection or repair.

The cap is provided on its upper surface with oppositely disposed pairs of projecting bosses 7 in which are formed the bearings 8 for the outwardly extending projections 9 of the cam levers 10. Preferably, and as shown, the bosses 7 have lugs 11 cast thereon on each side of the journal bearing, so that when the cam levers have been placed in position these lugs 11 can be bent over the bearings and hold the cam levers journaled in position. These cam levers are provided with the pro-

jecting cam portions 12 adapted to engage the cam surface 4 on the under side of the ring 2, to removably lock the cap in position.

13 is a circumferential channel cut in the cap 6 in which is mounted a packing washer 14 of rubber or other suitable material, the washer being held in position by the projecting ledge 15 on the lower side of the channel. As will be obvious from an inspection of the drawing, when the cap is locked in position by the cam levers 10, the bead 5 will be forced into the washer 14, thus compressing the body of the washer and forming a tight joint between the cap and the container.

16 is a pump barrel which is provided with a piston rod 17, the piston rod being formed of a section of pipe which passes through a stuffing box 18 at the upper end of the pump barrel, and the pipe is provided at its upper end with a handle 19 having the openings 20 extending therethrough and communicating with the pipe 17. The lower end of the pipe is screw-threaded, and on this portion are mounted the two pairs of clamps 21, 22. Between these pairs of clamps are mounted the piston packing 23, 24, the packing being shown as cup-shaped and extending in opposite directions, that is to say the upper packing has its free edge extending upwardly and the lower packing has its free edge extending downwardly. Between the two packings 23 and 24 I provide openings 25 in the pipe 17, whereby air may be supplied through the openings 20 to the space between the two piston packings. The lower end of the pump barrel is closed by a head 26.

27 is the exhaust tube which is preferably connected to the side of the pump barrel and which extends from the lower portion of the pump barrel up into the cap 6. At the lower end of the exhaust tube an opening 28 is provided, which connects the tube with the lower portion of the pump barrel. The cap 6 is transversely bored at 29, the opening 29 extending into the upper end of the exhaust pipe. The hole 29 at its outer end is enlarged, whereby a shoulder 30 is formed, against which a valve 31 can seat, the valve being held in position against the shoulder by a spring 32, which is confined between the back of the valve and a plug 33 threaded into the outer end of the opening.

34 is an opening extending from the opening 29 adjacent to the shoulder 30 through the cap, so that it will open into the container. By this construction it will be seen

that upon the down stroke of the pump piston air will be forced from the lower portion of the pump barrel into the exhaust pipe 27, and this pressure will force back the valve 31 5 and permit the air to flow through the opening 34 into the container. The cap is also transversely bored at 35, the opening thus formed extending into the pump barrel near its upper end at 36. The outer end of the 10 opening 35 is enlarged to form a shoulder 37 against which seats a valve 38 held in position by a spring 39 which is confined against the back of the valve, and the plug 40 threaded into the outer end of the opening 15 35. The cap is also bored from its lower edge up into the opening 35 adjacent to the shoulder 37, whereby upon the upstroke of the piston the valve 38 will be forced back and air can flow from the upper portion of 20 the pump barrel through the opening 35 and the opening 41 into the container.

It will be seen that air will flow through the openings 20 in the handle 19, through the hollow piston rod into the space between the 25 cups 23 and 24 and that because of the shape of these cups upon the upstroke of the piston the air will flow around the edges of the cup 23 into the lower portion of the barrel, while upon the down stroke air will flow around 30 the cup 24 into the upper portion of the barrel. Consequently the pump will be double acting and will force air into the container both upon the up and the down stroke.

42 is an enlargement cast upon the upper 35 portion of the cap 6 at one side. This enlargement is bored out transversely so as to form an opening extending from the under side of the cap through the same, and terminating at the upper side thereof. Into the 40 inner end of this opening is screwed the pipe 43 which extends down to the bottom of the container, and in the form of construction shown in Fig. 1 the valve 44 is screwed into the outer end of the opening. On to the end 45 of the valve or cock 44 the hose 45 terminating in the nozzle 46 can be readily attached. In the form of construction shown in Fig. 4 the cock 47 is located in the enlargement 42 and the hose 45 is connected directly onto 50 the outer end of the same.

From the foregoing description it will be apparent that when the cap 6 is removed all the operating parts of the construction will be removed, so that both the container and 55 the operating parts of the structure can be readily cleaned or repaired.

From the above description it is believed

that the operation of my device will be obvious.

While I have described what I believe to 60 be the preferred form of my invention, I desire to have it understood that many changes may be made in the form, construction and arrangement of parts without departing from the spirit thereof. 65

I claim:

1. In a fire extinguisher, the combination with a casing, of a cap for closing the casing, a pump comprising a barrel and a piston, mounted upon the cap, a pipe connected to 70 the barrel near its lower end and extending upwardly into the cap, a valve mounted in the cap for controlling the upper end of the pipe, and a delivery pipe mounted upon the cap and leading from the lower portion of the 75 casing to the exterior.

2. In a fire extinguisher, the combination with a casing, of a pump mounted therein, said pump comprising a barrel, a pipe forming a piston rod, a double piston mounted on 80 the lower end of the rod comprising oppositely disposed cup sections, the pipe being provided with an opening in its lower end extending into the space between the cup sections, a connection leading from the bottom 85 of the pump barrel into the upper portion of the casing and a second connection leading from the upper portion of the barrel into the casing and valves controlling the connections. 90

3. In a fire extinguisher, the combination with a casing, of a cap for closing the casing, a delivery pipe extending from the lower portion of the casing through the cap, a pump barrel mounted in the cap, a pipe forming a 95 piston rod mounted in the pump barrel, a handle on the outer end of the piston rod provided with openings extending therethrough and communicating with the upper end of the piston rod, a piston on the lower 100 end of the piston rod, the piston rod being provided with an opening on one side whereby air can pass into the pump barrel on one side of the piston, said pump barrel being provided with an opening on the other side 105 of the piston communicating with the interior of the casing and a valve for controlling said opening.

In testimony whereof I affix my signature in presence of two witnesses.

JAMES G. MASTIN.
